Primary Examiner — Terry Wallace(74) *Attorney, Agent, or Firm* — Florek & Endres PLLC(57) **CLAIM**

We claim the ornamental design for a double colander, as shown and described.

DESCRIPTION

FIG. 1 is a perspective view of the double colander of the present invention.

FIG. 2 is a top plan view of the double colander of the present invention.

FIG. 3 is a bottom plan view of the double colander of the present invention.

FIG. 4 is a front elevation of the double colander of the present invention.

FIG. 5 is a rear elevation of the double colander of the present invention.

FIG. 6 is a right side elevation of the double colander of the present invention.

FIG. 7 is a left side elevation of the double colander of the present invention; and,

FIG. 8 is an exploded perspective view of the double colander of the present invention.

The broken lines in the drawings represent unclaimed features.
